UNITED STATES PATENT OFFICE

2,555,620

ADJUSTABLE WIRE NETTING PROTECTOR

Martin W. Wenger, Arlington, Calif.

Application June 27, 1949, Serial No. 101,511

4 Claims. (Cl. 312—140.4)

1

This invention relates to store equipment and it is an object of the invention to provide a device to prevent shop lifting or other unauthorized removal of articles displayed on counters or the like, as in retail stores.

It is also an object of the invention to provide a device of this kind to be placed over merchandise upon a counter or the like to protect the same against unauthorized handling, yet in no way obstructing the merchandise to view.

A still further object of the invention is to provide a device of this kind which is adjustable as to length within certain limitations and wherein the device includes a front wall, a top wall and end walls, the rear face of the device being open to allow the sales person to have ready access to the merchandise.

The invention also has for an object to provide a device of this kind to be mounted on a counter or the like in a manner to be disposed over merchandise to prevent unauthorized handling and wherein the device is so constructed to allow a portion thereof to be moved into an inoperative position to facilitate dusting of the merchandise and the like.

The invention consists in the details of construction and in the combination and arrangement of the several parts of my improved device for protecting articles displayed on a counter or the like, whereby certain advantages are attained, as will be hereinafter more fully set forth.

In order that my invention may be better understood, I will now proceed to describe the same with reference to the accompanying drawings, wherein:

Figure 1 is a view from the rear of an equipment embodying the invention and in applied position upon a counter;

Figure 2 is a view in top plan of the device as comprised in Figure 1, but on an enlarged scale;

Figure 3 is a view in front elevation of Figure 2;

Figure 4 is an enlarged sectional view taken substantially on the line 4—4 of Figure 3, an associated counter being indicated in section;

Figure 5 is an enlarged detail sectional view taken substantially on the line 5—5 of Figure 3;

Figure 6 is an end elevational view showing the top wall raised;

Figure 7 is an enlarged fragmentary view taken substantially on the line 7—7 of Figure 4; and

Figure 8 is a view in perspective with a portion broken away of a brace herein employed and unapplied.

As disclosed in the accompanying drawings, the device comprises a front wall A, end walls B, and

2

a top wall C. The front wall A and the top wall C are adjustable as to length within certain limitations, as will hereinafter be more particularly referred to.

The front wall A in the present embodiment of the invention comprises two sections each of desired length and preferably of a height of approximately six inches although of course, this may be varied as the requirements of practice 10 may dictate.

One of the sections X of the front wall comprises a rectangular frame preferably of a heavy wire and including a top bar 1, a bottom bar 2, and end bars 3, all preferably formed of a single 15 length of wire of requisite gauge and rigidity. The bars 1 and 2 and the bars 3 are connected by the strands 4 of wire, adjacent strands 4 being spaced apart not more than one inch.

The end bars 3 have depending legs 5 each 20 formed at its outer or free extremity to provide an eye member 6 through which a screw may be passed to securely anchor the section X to the upper end portion of the counter 7.

The section Y of the front wall A, also includes 25 a rectangular frame of substantially the same dimensions as the section X and includes the top bar 8, bottom bar 9, and end bars 10 all preferably formed from a single strand of wire of desired gauge and rigidity. Associated with the bars 8, 9 and 10 are the cross strands 11 spaced 30 apart similar to the spacing of the strands 4.

The outer end bar 10 is provided with a depending leg 12 terminating in an eye member 14, whereby the outer end portion of the section Y may be secured to the counter after the sections X and Y have been adjusted lengthwise 35 one with respect to the other as the length of the counter may determine.

The inner end portions of the sections X and 40 Y of the front wall A overlap at all times and welded or otherwise secured to the inner bars 3 and 10 and the adjacent strands 4 and 11, respectively, are the flat strips 19 disposed in a direction lengthwise of the members X and Y.

45 These strips are positioned at the upper and lower portion of a section X or Y and the strips 19 of one section at all times overlie the strips 19 of the second section.

Each of the strips 19 is provided therealong 50 with the slot a preferably six inches in length. The slots a of the strips 19 of one section X or Y registers with the slots a of the strips of the second section and through which registering slots are disposed the clamping mediums b, herein disclosed as conventional bolts and nuts. The

slots *a* of one section in conjunction with the similar slots of the second section permit a relative adjustment of the sections *X* and *Y* for approximately twelve inches and the sections *X* and *Y* are maintained in selected adjustment by proper tightening of the clamping mediums *b*.

The top wall *C* is disclosed herein as also comprising two sections *S* each of a length substantially equal to the length of a front wall section *X* or *Y*. Each section *S* comprises a rectangular wire frame of desired gauge strength and has its side bars *15* and end bars *16* connected by the crossed wires *17* and *18* respectively with adjacent wires spaced apart not more than one inch.

The inner portions of the sections *S* overlap and said inner portions carry the strips *19* having the slots *20* through which extend the clamping screws *21* to enable the sections *S* to be selectively adjusted as determined by the adjustment of the sections *X* and *Y* of the front wall *A*.

The outer end bars *16* of the sections *S* at their forward ends are provided with the extended eye members *22* through which are freely directed the top bars *1* and *8* whereby the top wall *C* may be readily swung upwardly when it is desired to dust the merchandise on the counter or for the other necessary purposes.

Each of the end walls *B* comprises a rectangular frame of a length substantially equal to the width of the associated top section *S* and of a width substantially the same as the width of the sections *X* or *Y* of the front wall *A*. The frame on the end wall is also made from a single strand of material of requisite gauge and strength and substantially rectangular in form.

As herein embodied, each end wall *B* is independent of the walls *A* and *C* and includes a frame *23* of required dimensions with the lower corners of the frame provided with depending arms *23'* terminating in eyes *23a*. These arms *23'* overlie an end of the counter and the eyes *23a* are adapted to have disposed therethrough suitable anchoring members whereby the end sections will be maintained in applied position. Other ends of the frames *23* are provided with depending arms *24* terminating in eye members *25* to permit the same to be attached, when desired, to the counter or to serve as a supporting foot.

In referring hereinbefore to "front" it is to be understood that the same refers to the customer or public side of the counter or the like with which the device is employed.

From the foregoing it is believed obvious that the device when in working assembly upon a counter or the like, has its rear face open so that the sales person can readily handle merchandise in making a sale while at the same time the device serves as an effective guard against unauthorized persons in front of the counter having access to the merchandise on the counter except for visual inspection.

The top wall *C* can readily be swung upwardly to further facilitate access to the merchandise over which the equipment is disposed and to hold the top wall *C* in such required position, one or more brace members *M* may be used. As shown in Figure 8, the brace member *M* comprises an elongated rod *26* of desired gauge and length and which has a fork *27* at one extremity to engage from below a wire *17* or *18*, while the opposite extremity is pointed, as at *28*, to assure effective contact or engagement with the counter surface.

It is also desirable to effectively support from

below the sections *S* of the top wall *C* so that merchandise of material weight may be placed on the equipment or to withstand excessive pressure imposed upon the equipment.

Welded as at *29*, or otherwise securely held to the wires *17* or *18* at desired points on sections are the supports or props *P*. As illustrated in Figure 7, of the drawings, each support or prop *P* comprises two strips *30* and *31* having their inner ends overlapping with one of the strips, having a slot *32* disposed therealong and through which is directed a clamping medium *33* carried by the second member *31*. By this means the props may be adjusted lengthwise as the requirements of practice may dictate and the clamping means serves to hold the props in desired selected adjustment.

While the clamping means may vary, it is preferred that the same comprise a conventional bolt and nut, as illustrated.

The outer end of each of the sections *S* of the top wall *C* are continued by downwardly disposed extensions *E* substantially at right angles thereto and which provide means for closing the spaces between the outer ends of the top wall *C* and the tops of the end walls *B* when the top wall *C* is raised.

From the foregoing description it is thought to be obvious that a device for protecting articles displayed on a counter or the like constructed in accordance with my invention is particularly well adapted for use by reason of the convenience and facility with which it may be assembled and operated.

I claim:

1. A device for protecting articles displayed on a counter or the like against unauthorized removal, comprising a front wall, means carried by the lower portion of said wall for securing the same to the counter or the like, a top wall pivotally mounted on the upper portion of the front wall to permit raising and lowering of the top wall independently of the front wall, and end walls also having means for securing them to the counter, all of said walls being formed of reticulate sections so that the counter may be viewed through the device, brace elements carried by the top wall for contact with the counter or the like upon which the device is placed, and end members depending from the top wall to close the spaces between the end walls and top wall when the top wall is in raised position.

2. A device, as set forth in claim 1, wherein the front and top walls are each composed of overlapping longitudinal sections of wire screening with the sections clamped together to permit longitudinal adjustments on counters of different lengths, and wherein the brace elements are in the form of props depending from and rigidly secured to the sections of the top wall.

3. A device for protecting articles displayed on a counter or the like against unauthorized removal, comprising a front wall, means carried by the lower portion of said wall for securing the same to the counter or the like, a top wall pivotally mounted on the upper portion of the front wall to permit raising and lowering of the top wall independently of the front wall, and end walls also having means for securing them to the counter, all of said walls being formed of sections of open wire screening so that the counter may be viewed through the device, and props depending from and rigidly secured to the top walls for contact with the counter or the like upon which the device is placed.

4. A device, as set forth in claim 3, wherein the top wall has integrally connected end members in the form of depending, sector-shaped walls to close the spaces between the end walls and the top wall when the top wall is in raised position.

MARTIN W. WENGER.
